UNITED STATES PATENT OFFICE.

JOSEPH WANDER, OF ALBANY, NEW YORK, ASSIGNOR TO S. WANDER & SONS CHEMICAL CO., INC., OF ALBANY, NEW YORK, A CORPORATION OF NEW YORK.

PACKAGING PULVERULENT MATERIALS.

1,344,664.

Specification of Letters Patent. Patented June 29, 1920.

Application filed August 20, 1919. Serial No. 318,788.

To all whom it may concern:

Be it known that I, JOSEPH WANDER, a citizen of the United States of America, and resident of Albany, Albany county, and

5 State of New York, have invented certain new and useful Improvements in and Relating to Packaging Pulverulent Materials, of which the following is a specification.

This invention relates to the art of packaging pulverulent chemicals and other powdered or finely divided materials; and the objects and nature of the invention will be readily understood by those skilled in the art in the light of the following explanations of the method followed in packaging pulverulent materials, and of the accompanying drawings illustrating what I now believe to be the preferred mechanical expression or embodiment of my invention

20 from among other forms, constructions and arrangements within the spirit and scope thereof.

Various pulverulent materials, such chemicals, for instance, as chlorinated lime, etc., 25 particularly for household use, are usually packed more or less loosely, in air tight containers or cans, of various sizes. The chemicals are placed in such cans and sealed at the factory and thus reach the household

30 or consumer through various trade channels. These cans are usually sealed at the top by air tight plug closures that can be pried from the can tops to permit egress of the chemical contents.

35 Under certain conditions, pressure will be generated in such sealed cans of chemicals. It has been found that varying temperatures and weather conditions will sometimes cause the generation of gas in such cans, and that 40 such pressure when suddenly released by the removal of the closure plug, will cause what might be termed, an explosion discharging loose or powdered chemical contents into the room and over the person opening the can with possibly resulting damage and injury.

45 Whether or not such gas or pressure generation is the result of temperature and weather conditions, or other causes, the fact remains, that the packers of such chemicals have been confronted by a serious problem 50 owing to such scattering of powdered chemicals when some cans are opened and the resulting damage.

It is the object of my invention to provide 55 measures that will prevent such discharge

and scattering of the powdered contents of cans when opened even though the contents of the cans are under pressure, and to this end I provide means that will automatically prevent discharge of the powdered contents 60 when the can is opened while permitting the more or less slow or gradual discharge of gas or pressure.

With these and other objects in view, my invention consists in a novel manner of 65 packing such materials in cans and other containers, and in certain novel features in arrangement, construction and combination, as more fully and particularly set forth and specified hereinafter.

70 Referring to the accompanying drawings:

Figure 1 is a perspective view of a sealed package of pulverulent material such as chlorinated lime, the can being partially broken away to show the powdered contents, 75 the top closure, and the disk valve or guard.

Fig. 2 is a detail perspective view of the disk.

In the drawings I show any suitable can (container) having impervious wall 1, 80 permanent air tight usually metal bottom 2, and permanent usually metal top 3. The top 3 can be formed by a metal disk at its edge united to the top edge of the wall by a permanent air tight seam or crimp 4, 85 or in any other suitable manner. In the particular example illustrated, this metal disk is formed with a central opening surrounded by a depending annular edge or flange 5, and this opening is tightly sealed 90 to form an air tight closure by a removable plug or cap 6 of a usual or any other suitable construction. This is a common form of closure wherein the plug is forced into place under pressure and is held by friction. As 95 is well understood, the plug is removed by inserting a suitable instrument under the top flange of the plug and utilizing the same in prying the plug from the tin or other metal top to permit egress of the contents 100 of the can.

The can is more or less loosely filled with pulverulent or loose powdered chemical material *a*, such as chlorinated lime etc.

A disk 10 of any suitable material is arranged in the can resting loosely on the powdered contents, and this disk is of such dimensions as to be more or less freely movable vertically within the can between the loose mass of powdered material and the can 110

top. The outside diameter of the disk is less than the interior diameter of the can to permit vertical movement of the disk in the can and also permit upward leakage of 5 gas or air along the inner surface of the can wall past the edge of the disk. The disk is also imperforate at least to such an extent as to prevent the powdered material blowing therethrough.

10 The disk also is more or less flexible and composed of material that can be easily cut or severed to form an opening registering with the discharge opening in the can top for discharge of the powdered material after 15 the can has been opened.

As at present advised, I prefer to form the disks of paper or paper material.

When the plug or closure is pried from a can in which the generation of gas has produced pressure, the gas in seeking relief 20 through the can discharge opening, will almost instantaneously force the disk 10 upwardly against the under side of the can top and thereby prevent discharge or blowing of 25 powdered contents from the can, while permitting the gas to more or less slowly leak past the edge of the disk and between the top surface of the disk and the lower edge of flange 5 and find relief. The operator will 30 then by a knife blade or any other suitable instrument inserted through the mouth or discharge opening of the can, cut out and remove the central portion 10^a, of the disk so that the powdered contents can be 35 charged through the opening in the disk and the can mouth.

The top surface of the central portion of the disk preferably bears words or other indicia visible through the can mouth after 40 the plug has been removed, and imparting information that the disk must be cut through or removed to permit discharge of the powdered contents. For instance, I usually provide the top face of the disk with 45 instructions such as "Cut this out", although I do not wish to so limit my invention.

In packing the powdered chemical material, in accordance with my invention, the 50 cans are filled with the powdered chemical before the tops 3 are applied to the can bodies. The guard or barrier disks 10 are then placed in the cans resting on the powdered contents. After the cans have been 55 thus loaded and the disks applied, the cans are tightly sealed by application of the can tops 3 and plugs 6.

I do not wish to limit my invention to the

particular disk illustrated either in the matters of formation or relative dimensions, nor 60 do I wish to limit myself to the particular can type or structure illustrated.

In this connection, it is only necessary that the disk form a barrier or guard against powdered contents blowing through 65 the can discharge mouth, while permitting relief of the gas pressure. In the example illustrated, the diameter of the disk exceeds the diameter of the can discharge mouth and hence the disk is prevented from being 70 blown through the discharge mouth, as the paper material is of sufficient stiffness to prevent such deformation of the disk under the gas pressure as would permit passage of the disk through such mouth.

It is evident that various changes, modifications and variations might be resorted to without departing from the spirit and scope of my invention and hence I do not wish to limit myself to the exact disclosures hereof.

What I claim is:—

1. A sealed package of pulverulent material embodying a container having its discharge mouth sealed by a closure, and a loose barrier disk within the container constructed and arranged to permit gas relief and prevent powdered contents being blown through said discharge mouth when the closure is broken.

2. A sealed can containing loose powdered 90 chemical material characterized by an internal barrier between the contents and the can mouth constructed and arranged to prevent the powder being blown through said mouth by pressure within the can, when said 95 mouth is opened.

3. An original package of loose powdered chemical material embodying an air tight can having a discharge adapted to be opened for discharge of the can contents, said package having an internal barrier against passage of powdered contents, said barrier constructed and arranged to permit passage of air or gas under pressure, said barrier arranged within the can between said contents 105 and said discharge.

4. Means for preventing powdered contents being blown through the mouths of cans containing powdered chemicals by pressure generated within the cans, when said 110 cans are opened, said means consisting of a disk of paper material of greater size than the mouth of the can and loosely arranged within the can between said mouth and the powdered contents.

Signed. JOSEPH WANDER.
